ELEVATOR CONTROL SYSTEM

John Pedosin, Chicago, Ill., assignor to C. J. Anderson & Company, Chicago, Ill., a corporation of Illinois

Application March 29, 1930, Serial No. 440,045

11 Claims. (Cl. 187—29)

The present invention relates in general to elevator control systems.

One of the objects of my invention is to provide improved leveling means for leveling the 5 floor of the elevator car with the landing floor.

Another object is to provide leveling means that may be manually operated to cause the car to level itself with the floor even when the elevator doors are opened.

10 Another object is to provide leveling means of this character which will only be effective within a restricted zone near the floor.

Another object is to provide leveling means which by the operation of the controlling push 15 buttons will move the car either in an up or down direction, to bring it in a plane with the associated floor.

Another object is to provide an improved leveling circuit that while operative when the 20 elevator hatchway doors are open adjacent the associated floor will be ineffective in the event the car is not within the leveling zone.

A still further object of my invention is to provide a leveling circuit of this character which 25 is adapted to co-operate with any type of elevator control system, car switch, push button or fully automatic.

There are other objects of my invention, which 30 together with the foregoing will be described in the detailed specification which is to follow, taken into conjunction with the accompanying drawing, forming a part thereof:

In elevator control systems where no special 35 leveling means are provided it is always difficult to obtain level elevator stops. Some of the factors influencing this which are operative both in manual and automatic elevator operations are variations in the elevator load, fluctuations of line voltage and improper brake adjustments.

40 Many attempts have been made to provide automatic leveling means on elevators and automatic leveling systems of this character are always very complicated and expensive, in addition to being a cause of considerable maintenance expense.

45 A possible solution to these difficulties has been advocated which employs a pair of leveling push buttons in car for moving the elevator at a relatively slow speed in either direction to bring it level with the floor. This method requires 50 that the hatchway doors and the car gate be closed, which renders it very difficult to level as the floor level cannot be seen and also does not provide for variations in loading and unloading at a single floor.

55 In the construction and installation of eleva-

tors, either of the freight or passenger type, it is the present practice to provide a gate or barrier on the elevator car in addition to the hatchway doors, in order to obtain a maximum degree of safety. Elevators employing push button automatic operation are likewise furnished with this feature. Furthermore, state laws and municipal ordinances designed to insure the safety of elevator passengers and operators, provide that the elevator control mechanism be so designed and 60 arranged that the elevator cannot be moved in the event the elevator gate or hatchway door is open. In order to comply with these laws and to meet the demand of elevator trade, it has become a universal practice to provide elevator 65 control systems which will function in strict accordance with these rules. Since the elevator gate and sometimes the hatchway door obscures the floor selected from the vision of the passenger or operator, his task in manipulating the elevator 70 for properly levelling the same with respect to the adjoining floor is rendered difficult. It is therefore desirable to provide an arrangement whereby the elevator gate and hatchway doors 75 may be opened so as to enable the passenger or operator to observe the position of the elevator with respect to the floor selected and at the same time provide means for accurately moving the elevator so as to raise or lower it into proper 80 level with the floor. Although full automatic 85 operation of elevators has been provided in an effort to relieve the passenger or operator of the necessity for leveling the elevator, variation in level brought about by shifting of loads in unloading and loading, fluctuations in line voltage 90 and change in brake adjustments cannot be successfully accommodated under this system. The present invention provides means operable in a limited zone while the elevator gate and hatchway door is open so that the passenger can observe 95 the direction and necessity for leveling the car without in any way reducing the usual safety features required for elevator operation. This invention accordingly provides a leveling system as an adjunct to the usual automatic operation 100 and yet retaining safety factors of a push button elevator system. Furthermore, the present invention is designed to accomplish the results cited at a very nominal cost, whereby the major objection to leveling systems in small installations 105 is removed.

My invention eliminates all these disadvantages.

In practicing my invention, I provide a switch in the elevator car whose special function is to bring the leveling mechanism into play. Adja- 110

cent each floor in the hatchway I provide a pair of cams, one above and one below, of sufficient length to define the leveling zone. In addition, a switch is mounted on the elevator car and is adapted to be operated by the cams. This equipment in addition to the regular elevator control equipment permits the elevator to be levelled in an exceedingly simple and expeditious manner.

Referring now to the drawing comprising a single sheet, I have shown by means of the usual conventional diagrams sufficient of the apparatus and circuits to enable my invention to be readily explained and understood.

The reference character 1, designates the three line conductors which are employed to supply current to the elevator where three phase alternating current is employed.

Reference characters 2, 3, 4, and 5 designates alternating current relays of any usual or well known type. These relays are provided with a number of contacts which are adapted to be opened and closed when the relay is energized. The relays 2, 3 and 5 are the up and down direction relays and the motor connecting relay respectively. The hoisting motor is indicated diagrammatically at M and has associated with it a brake of the usual type, whose coil 6 is energized in parallel with one phase of the motor. A number of resistors 7, 8, 9 and 10 are employed for reducing the current flow in the circuit of certain of the relays under certain conditions. An up limit switch 11 of any usual or well known type is mounted in the hatchway as is the down limit switch 12. On the intermediate floor a switch 13 is mounted in the hatchway. This switch is of the double throw type and closes one of its sets of contacts when the elevator passes it in one direction and the other set of contacts when the elevator passes it in the other direction. When the elevator is at the intermediate floor both contacts are open.

Reference characters 14 to 16 inclusive, indicate switches that are operated by the hatchway doors at each floor and may be of any usual or well known type. The gate switch 17 may also be of any usual or well known type. Push buttons 18 to 20 inclusive, are mounted on the various floors, there being one push button for each floor. In the elevator car a plurality of push buttons or switches 21, 22 and 23 are mounted for control of operation of the elevator. An emergency stop switch 24 is also provided in the car. A switch 25 is mounted on the top of the car and has a projecting roller 26 that is adapted to contact with cams mounted adjacent to each floor in the hatchway. These cams are for leveling purposes and there being one cam above the floor and one below. In the intermediate position the switch 25 is opened. The switch 13 is mounted in the hatchway and is adapted to be operated by a cam on the car.

While I have illustrated my invention in connection with an elevator control system for a three story building, it will be appreciated that it may be readily adapted to a building having a greater number of stories or elevator stops.

Having briefly described the apparatus shown in the drawing, I shall now explain its detailed operation. In order to do this, it will be assumed that the elevator is standing at the first floor and that a passenger enters the car and after closing the hatchway door and the elevator gate, desires to ascend to the third floor, he indicates his intention by pushing the push button 21. A circuit is thereupon completed for the up direction

relay 2 over a path that may be traced from the supply conductor 30, relay 2, resistor 8, contacts of push button 21, hatchway door switches 14, 15 and 16 in series, elevator gate switch 17, emergency stop switch 24 to the supply conductor 31. The up direction relay 2 is energized over this circuit and operates to complete a circuit for the relay 5, by bringing the contact making member 33 into engagement with its associated contact member and connects the conductor 31 to the circuit of the motor M at the contact making member 34 and its associated contact member and prepares another point in the motor circuit at the contact making member 35 and its associated contact member. The operation of the contact making member 36 serves to establish a locking circuit for the relay 2 over a path that may be traced from the supply conductor 30, relay 2, third floor limit switch 11, resistor 9, contact member and contact making member 36, normally closed contacts 37, hatchway door switches 14, 15 and 16 in series, elevator gate switch 17, emergency stop switch 24 to supply conductor 31. The relay 2 is thus maintained energized after the push button 21 is released. The circuit of the relay 5 extends from the supply conductor 30, contact member and associated contact making member 33, relay 5, hatchway door switches 14, 15 and 16 in series, elevator gate switch 17, emergency stop switch 24 to the supply conductor 31. The relay 5 is energized over this circuit and operates to complete the circuit of the motor M at the contact making members 38 and 39. The motor M is energized and operates to bring about the movement of the car in the upward direction. The brake magnet 6 is energized in parallel with one phase of the motor circuit and serving to release the brake. The opening of the normally closed contacts 40 of the relay 5 serves to disable the floor push buttons 18, 19 and 20, as well as the circuit of the intermediate floor push button 22 in the cab. The elevator continues in an upward direction until the limit switch 11 is opened, whereupon the locking circuit of the relay 2 is opened at the switch 11 and this relay is deenergized to open the circuit of the motor M and also the circuit of the relay 5, relays 2 and 5 are immediately de-energized. The de-energization of the brake magnet 6 brings the elevator car to a stop approximately level with the third floor.

When the elevator door is opened the switch 14 is also opened as is the switch 17 by the operation of the elevator gate. Now the passenger may find that the elevator is not level with the third floor. It will first be assumed that the elevator has stopped above the third floor and it is necessary to lower it. The operation of the switch 11 has, of course, stopped the elevator within the leveling zone so that if the car is above the third floor the switch 25 will be closed, as a result of the engagement of the roller 26 with the upper cam. In order to lower the elevator, the passenger will depress the push button 23, thereby completing the circuit for the relay 3 over a path that may be traced from the supply conductor 30, relay 3, resistor 7, contacts of push button 23, switch 25, emergency stop switch 24 to the supply conductor 31. The relay 3 is immediately energized to complete a circuit for the relay 5 at its contact making member 41 to prepare points in the motor circuits at the contact making members 42 and 43. The operation of the contact making member 44 is without particular function at this time. The relay 5 is energized over a circuit which may

be traced from the supply conductor 30, contact member and associated contact making member 41, relay 5, contacts of push button 23, switch 25, emergency stop switch 24 to the supply conductor 31. The operation of the relay 5 serves to complete the motor circuit whereupon the brake magnet 6 is energized and motor causes the car to move in a downward direction. When the car is level with the floor the switch 25 is opened since the roller 10 26 falls in an open space between the two leveling cams. The circuit of the relays 3 and 5 is therewith opened and these relays are de-energized to disconnect the motor M and bring about the operation of the brake controlled by the brake magnet 6, consequently the car is brought level with the proper floor, even tho the elevator gate and the door at that floor has been opened which disables the normal operating circuits. By this provision it is possible for the passenger operating 15 the car to see when the elevator is level so as to ascertain whether he should portion the leveling operation and in what direction. If by some faulty adjustment of the control or brake, the car should move in a downward direction below the leveling zone, the fact that the elevator gate and door is opened would be of material disadvantage were it not for the fact that as soon as the elevator moves below, the leveling cam switch 25 is opened and the leveling circuits entirely disabled, 20 thereupon, the ordinary safety precautions are effective.

If the elevator should have stopped before reaching the desired floor, the operation is substantially the same as that before described. That is, the passenger when he opens the elevator gate and the floor door ascertains that the car has stopped below the floor level, he will therefore, press push button 21 which completes a circuit for the relay 2 thru the leveling switch 25. Relays 2 and 5 are operated to bring about the energization of the motor M and the leveling of the car with the floor. When the car has moved into the level position, switch 25 is opened and the relays 2 and 5 are de-energized to bring about 25 the de-energization of the motor M and the consequent stopping of the car.

When it is desired to move the elevator in a downward direction from the third floor from the car, the operation proceeds in a manner already similar to that described. In the event that there is a passenger on the second floor, desiring to call for the elevator with it standing on the third floor, the operation of the push buttons 19 serves to complete a circuit for the relay 3 over a path which may be traced from the supply conductor 30, relay 3, lower hatchway limit switch 12, intermediate switch 13, relay 4, contacts of push button 19, normally closed contacts 40, door switches 14, 15 and 16 in series, elevator gate switch 17, emergency stop switch 24 to the supply conductor 31. Relays 3 and 4 are energized over this circuit. Relay 3 is energized to bring about the operation of the relay 5 and the motor M as before described. The operation of the relay 4 serves to establish a locking circuit for itself at the contact making member 45 and for the relay 3 at this same contact. The operation of the contacts 37 serve to open a point in the normal locking circuit of the relay 3. When the elevator reaches the intermediate floor the switch 13 is operated and the circuit of the relays 3 and 4 is opened and these relays together with the relay 5 are de-energized to stop the operation of the 30 motor M. The elevator car may be leveled at the

intermediate floor in the same manner as has already been described.

It is thought that further operations will be obvious. It should be noted that the relay 4 is an intermediate floor relay and is only used when the intermediate floor is called for, the resistors 7, 8, 9, and 10 being substituted for it in other operations.

It will be appreciated that the elevator may be stopped at any time since all control circuits pass thru the emergency stop switch 24.

From the foregoing, it will be appreciated that I have evolved a very simple and efficient leveling arrangement for elevators in which the same control buttons may be employed as are used for standard operations and that the leveling circuit is effective even tho the elevator gate and floor doors may be opened for leveling operations only.

It is to be appreciated also that the leveling operation only occurs during the time the operator maintains his finger on one of the push buttons and then only until the car is levelled. In other words, accidental movement of the elevator prevented and the passenger in travelling into and out of the elevator is accordingly free of the hazards usually present when the elevator cage and hatchway door is open.

While the invention has been shown applied to a three floor elevator system, it will be obvious that any number of floors may be employed.

While this invention has been shown with an alternating current system, it will be obvious that the results noted may be accomplished with equal effect with direct current.

Furthermore, while automatic push button operation has been shown, it will be appreciated that my invention may be adapted to various kinds of elevator control, including car switch.

While I have shown and described a certain specific embodiment of my invention, I am aware that many changes, deviations and modifications may be made without departing from the spirit and scope thereof as indicated in the appended claims.

I claim:

1. In a control system, an elevator car, car actuating and stopping mechanism for moving said car and stopping it in association with any floor, manually operable control means for operating said car actuating and stopping mechanism to bring about such association, a pair of push buttons in said car, means controlled by one of said push buttons for lowering said car until level with the associated floor and means controlled by the other of said push buttons for raising said car until it is level with the associated floor.

2. In a control system the combination with an elevator hatchway, having an opening on a plurality of floors, an elevator car, car actuating and stopping mechanism for moving said car and stopping it at any floor, manually operable control means for operating said car actuating and stopping mechanism a pair of cams associated with each of said floors and mounted in said hatchway, one of said cams extending above said floor, defining a down leveling zone and the other of said cams extending below said floor and designating an up leveling zone, a pair of push buttons in said car, one assigned to the up direction control and the other assigned to the down direction control and means including one of said push buttons and one of said cams for operating said car actuating and stopping mechanism to bring it level with any floor.

3. In a control system, the combination with an

- elevator hatchway having an opening on a plurality of floors, an elevator car, car actuating and stopping mechanism for moving said car and stopping said car at any floor, controls for operating said car actuating and stopping mechanism at any floor, an elevator door closing said opening at each floor, a switch controlled by said door, mechanism controlled by said switches for disabling said car actuating and stopping mechanism controls, and manually controlled means comprising a pair of cams adjacent each floor and a switch actuated thereby, said means operative when said disabling means is effective for operating said car actuating and stopping means to level said car at any floor. 15
4. In a control system the combination with an elevator hatchway, having an opening on a plurality of floors, an elevator car, car actuating and stopping mechanism for moving said car and stopping it at any floor, an elevator gate for said car, a switch controlled by said gate, means operated by said switch for disabling said car actuating and stopping mechanism and leveling means operative from said car for leveling said car at any floor when said gate is open. 20
5. In a control system the combination with an elevator hatchway, having an opening on a plurality of floors, an elevator car, car actuating and stopping mechanism for moving said car and stopping it at any floor, a door on each of said floors closing said hatchway opening, a switch operated by each of said doors for disabling said car actuating and stopping mechanism, a gate on said car, a switch operated by said gate for disabling said car actuating and stopping mechanism and means controlled from said car for operating said car leveling and stopping mechanism to level the car at any of said floors when a hatchway door and the elevator car gate is open. 25
- 40 6. In a control system the combination with an elevator hatchway, having an opening on a plurality of floors, an elevator car, car actuating and stopping mechanism for moving said car and stopping it at any floor, a door on each of said floors closing said hatchway opening, a switch operated by each of said doors for disabling said car actuating and stopping mechanism, a gate on said car, a switch operated by said gate for disabling said car actuating and stopping mechanism, a pair of push buttons in said car and controlled means responsive to said push buttons for initial operation of said car actuating and stopping mechanism to level said car at the associated floor irrespective of the condition of said hatchway doors or gate. 50
- 60 7. In a control system the combination with an elevator hatchway, having an opening on a plurality of floors, an elevator car, car actuating and stopping mechanism for moving said car and stopping it at any floor, a door on each of said floors closing said hatchway opening, a switch operated by each of said doors for disabling said car actuating and stopping mechanism, a gate on said car, a switch operated by said gate for disabling said car actuating and stopping mechanism, a pair of push buttons in said car, a pair of cams mounted in said hatchway at each floor defining an up and down leveling zone and manually controlled means operative from said car including said cams for leveling said car at the 70
- associated floor when said elevator gate and hatchway door is open. 80
8. In a control system the combination with an elevator hatchway, having an opening on a plurality of floors, an elevator car, car actuating and stopping mechanism for moving said car and stopping it at any floor, a door on each of said floors closing said hatchway opening, a switch operated by each of said doors for disabling said car actuating and stopping mechanism, a gate on said car, a switch operated by said gate for disabling said car actuating and stopping mechanism, a pair of push buttons in said car, a pair of cams mounted in said hatchway at each floor defining an up and down leveling zone, 85
9. In a control system the combination with an elevator hatchway, having an opening on a plurality of floors, an elevator car, car actuating and stopping mechanism for moving said car and stopping it at any floor, manually operable control means for operating said car actuating and stopping mechanism a pair of push buttons in said car, means controlled by one of said push buttons for causing said car actuating and stopping mechanism to bring the car to the top floor, means controlled by the other of said push buttons for operating said car actuating and stopping mechanism to bring said car to the bottom floor and leveling means controlled by said push buttons for operating said car actuating and stopping mechanism to level said car at any floor. 90
10. In an elevator control system the combination of an elevator car, car actuating and stopping mechanism for moving said car and stopping it at any floor, a pair of push buttons in said car, means controlled by one of said push buttons for causing said car actuating and stopping mechanism to bring the car to the top floor, means controlled by the other of said push buttons for operating said car actuating and stopping mechanism to bring said car to the bottom floor, mechanism associated with each floor defining a leveling zone, a hatchway door on each floor, a switch adapted to be operated by each of said doors, means controlled by said switch for disabling said car actuating and stopping mechanism and means controlled by said push buttons when the car is at a leveling zone for operating said car actuating and stopping mechanism to level said car at the associated floor when the door is open. 105
11. In a motor control system, the combination with an elevator car, means for moving said elevator car including a motor, an electrical circuit for energizing said motor for moving said car and stopping it in association with any floor, a hatchway door on each floor having a switch associated therewith in series with the circuit aforesaid, and an electrical circuit in parallel with said first circuit for energizing said motor when said hatchway door switch is open to level the elevator car with the associated floor. 110
